VACUUM PUMP

Application filed August 21, 1926, Serial No. 130,598, and in Germany September 21, 1925.

This invention relates to high vacuum pumps of the type operating with mercury vapor on the ejector or diffusion principles. It has particular reference to the construction of all-metal pumps which are qualified for industrial employment, as distinguished from merely experimental or laboratory use, and which, accordingly, must be of sturdy construction to withstand rough or trying 10 usage.

The general object of the invention is the provision of a pump construction which will possess the requisite strength and have increased operating effectiveness and efficiency. 15 Another object is the provision of a construction which may be employed in either single stage or multistage pumps of the type specified.

Other and further objects and advantages 20 will be pointed out or indicated hereinafter or will be apparent to one skilled in the art upon an understanding of the invention or its employment in practice.

In the drawing,

25 Fig. 1 is a sectional elevation, taken on a diameter, of a single stage pump embodying the invention; and

Fig. 2 is a similar sectional elevation of a 30 two stage pump.

The invention is concerned with metallic pumps in which a gas is moved by an upwardly discharging stream of mercury vapor, whereby a very high vacuum may be produced in a connected vessel. The nature 35 of the invention will best be understood by reference immediately to the illustrative forms shown in the drawing, wherein the reference numeral 10 designates a tubular pump casing which is surrounded by a water jacket 11 wherein a cooling fluid may be circulated in contact with the outer surface of the casing 10. The casing 10 is provided adjacent 40 its lower end with an inlet connection 12 which is arranged to be placed in communication with the vessel to be evacuated. At its 45 upper portion the chamber within the casing 10 has an outlet through a connection 14 which is arranged to be placed in communication with the receiver of a preliminary vacuum pump which is effective to draw gases

from said chamber. At its lower end below the connection 12, the casing 10 is in communication with a generator 15, which contains a body of mercury 16, to be vaporized by heat from the heating element 17. Within 55 the casing 10, and about the communicating passage to the generator 15, is disposed a Venturi tube member 18, seating in the seal 19, and axially within this member projects a flow-directing member 20, the wall of 60 which, in cooperation with the tube 18, provides an annular nozzle 21. The member 20 may be supported in the tube 18 by thin fins 22, so arranged as to present minimum obstruction to flow of vapor through the tube 18. At its upper end, the member 20 is supported by a spring 24, which accommodates 65 longitudinal expansion of said member under heat. The water jacket is provided with an inlet 25 and outlet 26. The wall of the 70 member 20 diverges or flares toward the top, approaching the wall of the casing 10, and affording a restricted passage between the two at the level 27.

In operation, the air inlet connection 12 75 being placed in communication with the vessel to be evacuated, and the air outlet connection 14 being connected to a preliminary vacuum pump, the mercury 16 is vaporized by the heater 17, producing a pressure in the 80 generator, from which the vapor passes through the nozzle member 18, emerging from the nozzle 21 at high velocity. By this action air is drawn into the casing 10 through the inlet connection 12 and propelled toward 85 the top of the pump casing, becoming diffused meanwhile in the mercury vapor. The wall of the member 20 directs the vapor and air into close association with the cool wall of the casing 10, whereon the mercury is condensed. The effect is to propel the air to 90 the upper portion of the pump casing, whence it is withdrawn by the preliminary vacuum pump through the outlet connection 14. 95

In the embodiment illustrated in Fig. 2, the nozzle member 18 is supplemented with a concentric second stage nozzle member 28, projecting through it into the chamber of the generator 15 and sustained by the fins 29. 100

This second stage nozzle 28 extends up into the pump chamber and has its outlet end co-operating with the flow-directing member 20' to provide a second annular nozzle 30 at an elevation above the upper end of the nozzle member 18. In this construction, the operation is the same as in the one previously described, excepting that the action of the vapor discharged from the nozzle member 18 is supplemented, at a higher stage, by the jet from the nozzle 30, and the outer wall of the member 28, which diverges above the nozzle member 18 toward the pump casing 10, functions as a flow-directing member for guiding the vapor and air in contact with the cooling surface. It will be observed that the second nozzle member 28 is supplied with vapor from the generator independently of the nozzle member 18. It is to be understood that provision is made for the return of condensed mercury from the pump chamber to the generator in a well known manner.

The advantages attained by a pump embodying the invention include, in addition to strong construction, a high capacity for handling air, whereby the connected vessel may be rapidly evacuated and a high vacuum produced.

What I claim is:

1. In a vacuum pump, the combination of a pump casing having an air inlet and an air outlet, a generator, a nozzle tube leading into the pump casing from the generator and terminating between the air inlet and outlet, and a flow-directing member extending within the nozzle tube and diverging toward the casing wall.
2. In a vacuum pump, the combination of a pump casing, a generator, a nozzle tube extending into the casing and communicating with the generator, a flow-directing member extending into the nozzle tube and diverging toward the casing wall, and means for cooling the casing wall.
3. In a vacuum pump, the combination of a pump casing, a generator, a nozzle tube supplied from the generator and discharging in the pump casing, and a member having one end thereof extending into the discharge end of said tube and cooperating with the latter to form a nozzle.
4. In a vacuum pump, the combination of a pump casing, a generator, a nozzle tube supplied from the generator and discharging in the casing, and a flow-directing member having one end thereof extending into the discharge end of said tube and cooperating therewith to form an ejector nozzle, the other end of said member cooperating with the casing to form a contracting condensing throat.
5. In a vacuum pump, the combination of a pump casing, a generator, a nozzle tube supplied from the generator and discharging in the casing, and a closed flow-directing mem-

ber mounted concentrically in the tube and casing.

6. In a vacuum pump, the combination of a pump casing, a generator, a nozzle tube communicating with the generator and casing, a flow-directing member extending within the nozzle tube, and a yieldable support for said member accommodating its expansion.

7. In a vacuum pump, a casing, a vapor generator, means disposed in said casing and providing a nozzle for receiving the vapor from said generator, and yieldable means associated with said nozzle means and providing a support therefor while permitting of conditions of unequal expansion and contraction between the same and said casing.

8. In a vacuum pump, a casing, a vapor generator, a tube disposed in said casing and receiving vapor from said generator, and a member having one end thereof disposed in said tube to provide therewith a nozzle, and spring means providing a support for the other end of said member while permitting of conditions of unequal expansion and contraction between the same and said casing.

9. In a vacuum pump, a casing, a vapor generator, means disposed in said casing providing a nozzle for directing the vapor formed in said generator, a flow-directing member extending into said nozzle and having diverging sides to provide an annular passage-way with said casing, and means for yieldingly mounting said flow-directing member within said casing.

In testimony whereof I have hereunto subscribed my name this 5 day of August, A. D. 1926, at Zurich, Switzerland.

OSKAR SEITZ.
